UNITED STATES PATENT OFFICE.

WILLIAM HARDCASTLE BAYNARD, OF BOSTON, AND FREDERICK WILLIAM EAGER, OF BROOKLINE, MASSACHUSETTS, ASSIGNORS TO HARRY H. BECKWITH, OF BROOKLINE, MASSACHUSETTS.

SHOE HEATER.

Application filed April 12, 1921. Serial No. 460,700.

To all whom it may concern:

Be it known that we, WILLIAM HARDCASTLE BAYNARD and FREDERICK WILLIAM EAGER, citizens of the United States, and, respectively, residents of Boston, in the county of Suffolk, State of Massachusetts, and of Brookline, in the county of Norfolk and State of Massachusetts, have invented new and useful Improvements in Shoe Heaters, 10 of which the following is a specification.

This invention has relation to heaters for use in the manufacture of shoes and has for its object to provide certain improvements therein as will be subsequently explained.

Heretofore, in the assembling of the parts of a shoe preparatory to the pulling-over operation, it has been customary, when stiffened boxes are employed, for the operator, known as the assembler, to assemble loosely on a last the innersole and the upper, and, after daubing a flexible, previously unstiffened box blank with shellac or other compound which sets on the volatilization 20 of the solvent, to insert the blank between the lining and the tip or cap and stick it temporarily in place. The assembler then places the thus assembled shoe on a rack, from which it is subsequently withdrawn by 25 an operator, known as a puller, who pulls over the shoe, that is, draws the upper about the last by hand or by aid of an appropriate machine known as a pulling-over machine, and fastens the upper to the innersole at 30 various points. This entails the removal of the shoe rack from the station where the assembler is located into proximity to the puller. When previously stiffened blanks came into use, namely fibrous blanks im- 35 pregnated with a stiffening agent adapted to be softened by the application of heat, the procedure hereinbefore outlined could not be followed without heating the blank, so that it has now become a part of the puller's 40 duty, after the flat stiff blank has been assembled in the upper and secured in place by a stapling or stitching machine, to heat the blank preparatory to the pulling-over 45 operation. This thus entails a double duty laid upon the puller and slows down his 50 production, since a part of his time must be devoted to placing the assembled shoes on the heater and removing them therefrom, which should properly be devoted

merely to the pulling-over operation. 55 Waste motion should be eliminated both for the purpose of preventing fatigue, increasing the dexterity of the operator and for increasing his output.

This invention has for its object to provide instrumentalities by which the blanks may be heated and softened by one operator, e. g. the assembler, who assembles the upper and innersole on the last and presents it in a heated condition to the puller, whose sole 60 function then is to place the assembled shoe in the pulling-over machine and subject it to the pulling-over operation. For this purpose, a rack or table, having provision for supporting a double line or row of op- 65 positely-facing shoes in proximity to heating elements, has been provided, one of the lines of shoes being adjacent the station of the assembler while the other is in convenient position for the puller, the rack or 70 table being so constructed that the positions of the two rows or lines may be interchanged at will. By this means, the assembled shoes may be subjected to the heating operation, and, while so heated, may be moved into convenient position for the puller who may remove them from the rack 75 in immediate condition for the pulling operation, the racks being successively in receiving and unloading positions. In order to 80 facilitate the heating operation, prismatic heaters have been designed, each having a heat conducting upper face for supporting the toe portion of the upper of an assembled shoe while the toe of the last may extend 85 thereunder where it is protected from the heat.

For a more complete understanding of this invention; together with other objects and advantageous details and combinations of parts, drawings illustrating a construction embodying the invention are shown herewith, in which—

Figure 1 shows a rotary combined shoe rack or table and heater having a plurality 100 of shoe-supporting elements and heating elements associated therewith.

Figure 2 is a diagrammatic view illustrating the location of the assembler and the puller, and the relation of the pulling over 105 machine and the rotary combined shoe rack and heater.

Figure 3 represents an end view of the

stationary heater which may form a part of the equipment.

Figure 4 represents a plan view of the combined rack and heater.

5 Figure 5 is a transverse vertical section on the line 5—5 of Figure 4 through the upper part of the same.

10 Figure 6 shows the electrical connections for connecting the heating elements with conductors leading from the source of current.

15 Figures 7 to 10 inclusive are diagrams of the electrical circuits, showing how the heat generated in the heater may be regulated and controlled through the medium of a suitable switch.

20 Referring more particularly to Figures 1, 4 and 5, 1 represents a support or standard which may be fixed to the floor, which has

25 near its upper end a collar 2 made fast thereon by a set-screw 3. This collar is arranged to support a table 4 for rotation on the support 1, a bearing plate 5 being made fast to the lower face thereof by means of screws

30 6 (see Figure 5), and having a flange 7 closely surrounding the support 1 and resting on the upper surface of the collar 2. The upper end of the support 1 is screw-threaded for the reception of a cap 8 which bears

35 against the upper face of the table 4 to prevent its removal therefrom. The under side of table 4 is provided with a series of oppositely-extending guideways 9 in which are adjustably mounted slidable supporting

40 members 10 which may be formed, if desired, of sections of pipe. At their outer ends, the members 10 have fixed thereto the T-fittings 11 for adjustably supporting pipes or rods 12 extending vertically therethrough

45 and carrying at their upper ends T-fittings 13. As shown in Figure 4, a pipe or rod 14 is supported by a pair of fittings 13 and extends longitudinally of the table on opposite sides thereof. Adjacent opposite sides of

50 the table are a series of upstanding brackets 15 which support on their upper surfaces a pair of heaters 16 extending in parallel relation to the pipes 14 and spaced by the brackets 15 sufficiently above the upper surface

55 of the table 4 to allow the toe of a last, the heel end of which is supported on one of the pipes 14, to extend thereunder. As shown in Figures 1 and 5, these heaters are

60 in the form of substantially triangular prisms having two faces thereof formed of a metallic plate 17, lined with a sheet of asbestos or similar material 18, ventilation openings 19 being provided through the walls thereof at intervals if desired. The

65 third face of each heater comprises a strip of asbestos 20 and a wire netting 21 carried on its upper surface, this netting and the sheet 20 being made fast to the plate 17 at intervals by screws 22. As shown in Figure 5, a bracket 23 may be mounted within

the heater, on which may be supported an electric heating element 24 of any suitable description. In order, however, to allow a more flexible control of the heat developed in the heater, it is deemed preferable to use 70 a pair of heating elements, as shown more particularly in Figure 1. By reference to this figure also, it will be seen that the netting 21 furnishes a foraminous heated support of heat conducting material of even 75 temperature throughout, on which the toe portion of an assembled shoe, with the stiffener affixed thereto, may be held in substantially flat condition as it is received from the manufacturer during the heating operation as shown at *a* on Figure 1, while the toe of the last is positioned beneath the heater out of the way and substantially unaffected thereby, as shown at *b*.

80 In order to provide electrical connections for each heater and allow the table 4 to be turned, connections as now to be described may be employed.

85 Referring to Figure 5, the cap 8 is centrally perforated for the reception of a fiber sleeve 40 within which is fixed a metallic sleeve 41. Within this metallic sleeve is a second fiber sleeve 42 projecting above the end of the sleeve 41, and through the sleeve 42 is passed a metallic rod 43 which extends above the upper end of the fiber sleeve 42. A conducting slip ring 44 is rotatable on the end of the rod 43 and bears against the upper end of the fiber sleeve 42, and a similar ring 45 surrounds the upper end of the sleeve 41 and bears on the upper end of the fiber sleeve 40. As shown in Figure 6, each ring 44 and 45 comprises a strip of metal, as shown at 46 and 47, which is bent around its respective conducting element, and the free end adjustably clamped in position by screws 48 and 49. Strips 46 and 47 may then be connected to opposite terminals of the heating elements, the turning of the table 4 causing the strips 46 and 47 to turn relative to their telescopically arranged conductors 43 and 41, while retaining electrical continuity therewith. The lower ends of the rods 43 and the sleeve 41 are connected to a pair of wires 50 and 51 which lead down through 100 the support 1 and to any suitable source of electrical power.

105 Referring now to Figure 4, the electrical connections to the heating elements from strips 46 and 47 may be as follows. These strips are made fast to terminals 52 and 53 of a panel board 54, connecting through fuses 55 and 56, to a double-story distributing switch 57 controlling the connections to the terminals 58, 59 and 60, to which are attached the conductors leading to the heating elements.

110 In Figures 7 to 10 are shown wiring diagrams illustrating the different connections which may be made by manipulation of the 115

switch 57 for various degrees of heat required; in Figure 7, the heating elements being shown connected in parallel, by which a high heat is obtained; Figure 8 showing one heating element only in circuit for a medium heat; Figure 9 showing the two elements in series for a lower heat; and Figure 10 showing the switch open for no heat. At 61 may be provided a lamp in a shunt circuit which 10 serves as a visible indication of the particular degree of heat for which the switch is positioned by means of the intensity of its light. Detailed description of the switch, whereby these connections are made, is 15 deemed unnecessary, as such switches are well known in the art.

Referring now to Figure 2, at A is indicated the station for the shoe-assembler in a shoe factory, the rack or table above described being indicated at B. At C is shown the station for the puller and at D is shown the position of the pulling-over machine. By inspection of this figure, it is evident that the assembler may take the lasts and 25 shoe uppers from the rack, assemble them, together with the stiffeners, and place them along one side of the table or rack as shown in Figure 2, where the toe stiffeners may be subjected to heat from the heaters as above described. One side of the table having 30 been filled with the thus assembled shoes, the table may then be rotated about its support to present the shoes in convenient position for the puller at C, who may take these 35 shoes, while they are still subject to the action of the heaters, and place them in the pulling-over machine D to perform the pulling-over operation. It should be noted that the assembler holds the shoe by the heel portion 40 as he places it on the heater, this being the natural position for holding during the insertion of the toe stiffener, and that the shoe is presented to the puller in position to be removed by grasping the heel portion 45 in convenient position for immediate insertion in the pulling-over machine. The handling of the shoe is thus rendered natural and easy, and useless or lost motions eliminated. At E is shown a stationary heating 50 member on which the assembler may place the stiffeners for a preliminary heating before assembling them in the shoes if desired, the arrangement of this heating member being shown in Figure 3. Referring to this figure, a pair of bracket arms 55 70 support at their upper ends a triangular heater 71, which may, if desired, be constructed in the same manner as the triangular members 16 above described, the supports 70 having inwardly-turned upper portions to engage beneath the extended edges of that face of the heater comprising the wire netting 21.

Having thus described an embodiment of 60 this invention, it will be evident to those

skilled in the art that many changes and modifications might be made therein without departing from its spirit and scope as defined by the appended claims.

We claim:—

1. In combination, a shoe holder, a heater carried by said holder, and means for facilitating the movement of said holder while the shoe is being heated thereon to present the shoe at any of a plurality of positions. 70
2. In combination, a shoe holder rotatable about an axis, and a shoe heater carried by said holder eccentric to said axis. 75
3. A device of the class described comprising a table mounted to turn about a vertical axis, a plurality of shoe supports mounted on said table, and a heater carried adjacent each shoe support. 80
4. A device of the class described comprising a table mounted to turn on a vertical axis, a series of heaters supported adjacent the edge of said table, and frames extending from said table for supporting assembled shoes with their toe portions extending adjacent said heaters. 85
5. A device of the class described comprising, in combination, a vertical support, a table mounted to turn on said support, a series of electric heaters carried by said table, a series of members for supporting shoes in position to be heated by said heaters, and electrical connections to said heaters extending through said support and constructed and arranged to maintain electrical continuity with said heaters while permitting the turning of said table. 90
6. A device of the class described, in combination, a movable shoe holder, electrical means to heat a shoe thereon, and means for insuring a supply of electric current to said heating means while said holder is being moved. 105
7. A device of the class described comprising, in combination, a movable table, a series of heaters placed on said table, and a series of shoe supports carried by said table each positioned to support an assembled shoe with the toe of the last extending under a heater and the shoe upper resting thereon. 110
8. A heating device comprising a support, a frame spaced above said support to receive the toe of a last of an assembled shoe therebetween, and a heater carried by said frame and on which the toe portion of the shoe upper may rest. 115
9. A heating device comprising a support, a frame spaced above said support, and a substantially triangular prismatic heater carried by said support in position to support the toe portion of an assembled shoe thereon while permitting the toe of the last to extend thereunder. 120
10. A shoe heater comprising a vertical support, a table pivoted on said support, a pair of telescopically arranged spaced con- 125
11. A device of the class described comprising a table mounted to turn about a vertical axis, a plurality of shoe supports mounted on said table, and a heater carried adjacent each shoe support. 130

- ducting elements carried by said support and projecting to different distances therefrom, an electric heater carried by said table, and slip rings engaging said conducting elements and connected to the terminals of said heater.
11. A device of the class described comprising, in combination, a plurality of shoe supports, means to heat shoes on said supports, and means whereby said supports may be moved in succession into position for shoes to be placed thereon.
12. A device of the class described comprising, in combination, a plurality of shoe supports, means to heat shoes on said supports, and a carrier for said supports movable to permit shoes to be placed on successively presented supports at one position and removed therefrom at another position.
13. A shoe heater, comprising, in combination, a standard, a support rotatably carried by said standard, an electrical heating appliance on said support, stationary conductors carried by said standard, and slip ring connections from said conductors to said appliance.
14. A heater for the toe of an assembled shoe comprising a receptacle having a top face for supporting the toe portion of the shoe upper, a lower face sloping downwardly and rearwardly from said face and beneath which the toe of the last may extend, and a heating element within said receptacle.
15. In a device for heating shoes a heater comprising a prismatic casing and a heating element carried within said casing.
16. In a device for heating shoes a heater comprising a prismatic casing, and a heating element extending longitudinally within said casing.
17. In a device for heating shoes a heater comprising a prismatic casing, a support for articles to be heated mounted on one face of said casing, and a heating element within said casing.
18. A shoe heater comprising a prismatic casing, a support for a shoe to be heated mounted on one face of said casing, a plurality of electrical heating elements carried within said casing, and means for connecting said elements in various relationships to a source of electrical energy whereby the heating effect of said elements may be varied.
19. A shoe heater comprising a prismatic casing, a wire netting over one face of said casing to furnish a support for a shoe to be heated, and a heating element within said casing.
20. A device for heating shoes comprising a casing having a flat top comprising a fo-raminous heat conducting member for supporting a shoe to be heated, and a heating element within said casing.
21. In a device for heating shoes a heater comprising a heating member constructed and arranged to heat the toe portion of the upper of an assembled shoe while permitting the last to be substantially unaffected thereby.
22. A device of the class described comprising a support, a shoe holder on which a shoe may be placed in one position relative to a shoe operator at one station, and movable on said support to present the shoe for removal in the same relative position to another shoe operator at a different station.
23. A device of the class described comprising, in combination, a heater, means for supporting an assembled shoe in proximity to said heater to expose the box toe blank in substantially flat condition to the heater, and means whereby said means and heater may be moved bodily together.

In testimony whereof we have affixed our signatures.

WILLIAM HARDCASTLE BAYNARD.
FREDERICK WILLIAM EAGER.
